F. J. BROWNELL

AUTOMATIC TELEPHONE SWITCH

Filed May 11, 1922

Inventor:
Frederick J. Brownell

by W. E. Beatty, ATT'y.

UNITED STATES PATENT OFFICE.

FREDERICK J. BROWNELL, OF QUEENS, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed May 11, 1922. Serial No. 560,011.

To all whom it may concern:

Be it known that I, FREDERICK J. BROWNELL, a citizen of the United States, residing at Queens, in the county of Queens, State of New York, have invented certain new and useful Improvements in Automatic Telephone Switches, of which the following is a full, clear, concise, and exact description.

10 This invention relates to automatic switching apparatus and more particularly to coordinate switches of the type adapted for establishing connections in an automatic telephone exchange system.

15 The invention is particularly adaptable to a switching system of the type disclosed in a co-pending application of Charles L. Goodrum and John N. Reynolds, Serial No. 486,442, filed July 21, 1921, or the British

20 patent issued to Western Electric Company, Limited, No. 183,438, accepted September 6, 1923, but it will be apparent to those skilled in the art that this invention may be applied equally well to perform other switching

25 functions with few changes in the operating circuit.

The object of this invention is to provide an economical and improved form of coordinate switch which will be simple, durable and reliable to operation.

In accordance with the foregoing object, the principal feature of this invention relates to the provision of a novel mechanism for selectively operating the active contacts in a coordinate switch structure, comprising in general, a lifting arm provided with a cam and a hook-shaped portion which is adapted to operatively engage an operating member, thereby to move a card of insulation material through which the active contact springs extend, the operation of the card being effective to permit the active contacts to move into engagement with their associated passive contacts.

45 Other features and advantages of the invention will appear from the following detailed description, and from the claims appended thereto, reference being had to the accompanying drawing in which Fig. 1 is a partial front assembly view of said switch. Fig. 2 is a right-hand side view thereof showing the lower set of contacts in operated position; and Fig. 3 is a perspective view of a set of contacts showing the rela-

tive normal positions of the selective and 55 operating bars.

The sets of grid conductors comprising the wires 1, 2, 3, 4 and 1', 2', 3' and 4', etc., are securely fastened at their ends to fixed members, not shown. Supports 6 are of insulation material and are disposed at right angles to the direction of the length of the grid conductors and on them are mounted the flexible wire contact springs 8, 9, 10, 11 and 8', 9', 10', 11', etc. The supports 6 may be of considerable length and may carry any desired number of sets of contact springs 8, 9, 10, 11, etc., depending upon the switch capacity desired. For simplicity of illustration, however, only two such sets are 65 shown on support 6 in the side view of Fig. 2. The free ends of each set of contact springs 8, 9, 10, 11, etc., extend through oblique apertures 12 in a tie member or card 13, each of which is freely mounted on a resilient support 14, said resilient support being fixed at one end portion to the support 6. The free end 14' of resilient support 14 normally rests on the topmost conductor of its associated set of grid conductors, thus 70 acting as a back stop for the active contact wires. The resilient support is adjusted normally to hold the cards 13 and contact springs down out of contact with the grid conductors. With each vertical row of active contact sets there is associated a vertical rotatable bar 15 which is provided at 75 one end with an armature 16 arranged to be attracted by an electromagnet 17, whereby the bar 15 is rotated out of its normal position in response to each energization of said electromagnet. On each vertical bar 15, there is provided a number of resilient guides 18 each individual to a set of contact springs, and each provided with a back stop 80 19 to hold said guides, when operated, in a fixed position during the upward movement of arm 23, the said guide being freed in the opposite movement of arm 23 to permit the latter to restore to normal while said guide is in its off-normal position.

With each set of link conductors 1, 2, 3 and 4, there is associated a horizontal rotatable bar 20, which is provided with an armature 21 and an electromagnet 22, whereby the bar is rotated from normal to off-normal position. Each horizontal bar is provided with a number of arms 23 which are resili-

ent in the horizontal direction. Each of these arms 23 is individually associated with a set of active contact wires and a guide 18.

The operating cards 13 are each movably engaged in a channel-shaped guide 25 held secure on the switch frame (not shown) in any well known manner. The said cards, as above observed, are each mounted on a resilient support 14 adapted to be operatively engaged by the hook 26 of arm 23, but it will be noted that normally arms 23 are free to move in a vertical path to one side of their respectively associated resilient supports 14. This is true, however, only 15 while the associated guide 18 is in its normal position as shown at 27, Fig. 1, wherein the arm 28 is shown in its off-normal ineffective position.

When the vertical bar 15 is rotated out 20 of its normal position by electromagnet 17, the end portions 29 of the guides 18 are moved into operable engagement with the cam portions 26' of their associated arms 23. The rotation of bar 20 results in the 25 lifting of the operating card 13 by means of the engagement of the resilient support 14 with the hook 26 so as to permit the active contact wires 8, 9, 10 and 11 to engage the grid conductors 1', 2', 3' and 4', respectively. 30 The operated horizontal bar together with arm 23 thereon remain in their off-normal position throughout the duration of the connection, but the vertical bars 15 may be immediately restored to normal. The cam portion 26' in its operated position is 35 entirely clear of its associated guide 18 so that any subsequent movement of the guide arm is ineffective to disturb the connection already established.

40 What is claimed is:

1. The combination in a switching mechanism, of cooperating active and passive contacts, an operating card through which said active contacts pass, a movable support for 45 said operating card, an operating member normally movable in a path ineffective to engage said support, and resilient means for causing said operating member to deviate from its path to engage said support and 50 cause the actuation of the active and passive contacts.

2. The combination in a switching mechanism of cooperating active and passive contacts, a flexible element for supporting said active contacts, said active contacts being normally out of engagement with said passive contacts, a device having a hooked portion and normally rotatable in a path ineffective to cause the operation of said active contacts, a bar for moving said device, and another bar cooperating with said first bar for causing said device to deviate from its normal path to engage said flexible element to actuate said active contacts.

65 3. A coordinate switch comprising sets of

passive contact members, sets of active contact members, an arm for operating said members, a cam carried by said arm, said arm being normally operable ineffectively with respect to said active contact members, 70 a rotatable guide, and means for rotating said guide to cause a subsequent operation of said arm to be effective with respect to said active contact members.

4. A coordinate switch comprising sets of 75 passive contact members, sets of active contact members normally out of contact with the first mentioned sets, a resilient arm for operating said members, a cam carried by said arm, said arm being normally movable 80 in a path wherein it is ineffective to operate said active members, and a resilient guide cooperating with said cam which when operated is effective to cause said arm to deviate from its normal path to operate said active 85 contacts.

5. A coordinate switch comprising sets of passive contacts, sets of active contacts normally out of contact with the first mentioned sets, a resilient arm having a hooked portion for operating said active contacts, said arm being normally movable in a path wherein it is ineffective to operate said active contacts, means for operating said arm comprising a resilient guide, and means for 90 moving said guide into the path of said arm whereby said arm is caused to deviate from its normal path to operate said active contacts.

6. A coordinate switch structure comprising sets of passive contacts, sets of active contacts normally out of contact with the first mentioned sets, a resilient arm having a hooked portion for operating said active contacts, said arm being normally operable 100 ineffectively with respect to said active contacts, a resilient guide, and means for moving said guide whereby said guide is operable to cause a subsequent operation of said arm to effect connection between said contacts, said connection being unaffected during its continuation by subsequent operation of said guide.

7. In a coordinate switch structure sets of passive contacts arranged in a row, sets of active contacts arranged in a row coordinate to the first mentioned row, a bar associated with said row of passive contacts, a plurality of resilient operating arms mounted on said bar, a cam carried by each of 110 said arms, a bar associated with said row of active contacts, a resilient guide carried by said bar, means for operating the first mentioned bar to move said resilient arm, and means for operating the second mentioned bar to move said guide, a movement of said guide followed by a movement of said resilient arm being effective to interengage said active and passive contacts.

8. In a coordinate switch structure, a 115

- row of sets of passive contacts, a row of sets of active contacts arranged on upright supports disposed coordinately to said row of passive contacts, a tie member for each set of active contacts, a movable support for each of said members, means for operatively engaging said last mentioned supports comprising a pair of coordinately disposed rotatable bars, a resilient operating arm 10 mounted on one of the bars of said pair, a cam carried by said arm, and a guide carried by the other bar of said pair of bars, said guide in its off-normal position being disposed in the normal path of said resilient 15 arm whereby said resilient arm in its movement from normal is caused to deviate from its normal path to effect interengagement of said contacts.
9. In a coordinate switch, sets of passive 20 contacts, sets of active contacts normally out of engagement with said passive contacts, an operating card for each set of active contacts and through which the latter pass, a flexible support for each of said operating 25 cards, a rotatable bar carrying a plurality of resilient arms each having a hooked portion and each associated with an active contact set, flexible guides, means for moving said resilient arms freely with regard to 30 said active contact sets, and means effective upon the actuation of said flexible guides and a subsequent movement of a particular one of said resilient arms for causing the latter to deviate from its path to thereby 35 selectively operate the associated active contact set.
10. In a coordinate switch structure, sets of passive contacts, sets of active contacts, each set of active contacts being associated 40 with a set of passive contacts, a tie member for each set of active contacts, a movable support for each of said members, and a se-
- lective mechanism for operating said active contacts, including a vertically disposed rotatable bar, a resilient arm on said bar 45 adapted to be flexed into engageable relation with said movable support, a second rotatable bar disposed coordinately to the first mentioned bar, and a resilient guide which when operated is effective to cause said arm 50 to deviate from its normal path to engage and move said support to effect engagement between said sets of contacts.
11. In a coordinate switch structure, sets of passive contacts, sets of active contacts, 55 a selective mechanism for operating said active contacts including a movable bar carrying a plurality of flexible arms, a rotatable bar, a resilient guide on said rotatable bar, means carried by said rotatable bar to hold 60 said guide in a fixed position relative to the off-normal movement of one of said arms, and means rendered effective when said last mentioned arm is moved subsequent to the rotation of said rotatable bar for causing 65 said contact sets to interengage.
12. In a coordinate switch structure, sets of passive contacts, sets of active contacts, a selective mechanism for operating said active contacts including a movable bar carrying a plurality of flexible arms, a rotatable bar, a resilient guide on said rotatable bar, 70 means carried by said rotatable bar to hold said guide in a fixed position relative to the off-normal movement of one of said arms, and means rendered effective when said last mentioned arm is moved prior to the rotation of said bar for rendering such arm 75 ineffective to cause interengagement of said contact sets.
- In witness whereof, I hereunto subscribe my name this 6th day of May A. D 1922.

FREDERICK J. BROWNELL.
